UNITED STATES PATENT OFFICE

WILLIAM S. ANDREWS, OF SCHENECTADY, NEW YORK, ASSIGNOR TO GENERAL
ELECTRIC COMPANY, A CORPORATION OF NEW YORK.

ELECTRIC HEATER.

1,022,016.

Specification of Letters Patent. Patented Apr. 2, 1912.

Application filed January 14, 1911. Serial No. 602,804.

To all whom it may concern:

Be it known that I, WILLIAM S. ANDREWS, a citizen of the United States, residing at Schenectady, county of Schenectady, State 5 of New York, have invented certain new and useful Improvements in Electric Heaters, of which the following is a specification.

This invention relates to electric heaters and has for its object the provision of means whereby the current will be automatically cut off from the electric heater when the temperature reaches a predetermined point and cannot be again turned on until the temperature falls to the desired point.

My invention relates more specifically to electrically heated flatirons and the like. In devices of this sort it is often desirable that some means be provided whereby the heat will be cut off from the iron in case the temperature exceeds a certain degree.

In my previous application, Serial No. 538,729, filed January 18, 1910, I have disclosed an electric flatiron in which an automatic switch is provided for cutting out the heating unit at a predetermined temperature. In said application I also provide means for again closing the switch as well as means whereby the switch may be opened by the operator at any time. While this arrangement is perfectly satisfactory for general purposes, it has been found that under some conditions it is unsatisfactory to have the parts so arranged that the two contacts can be brought together by the operator so as to close the switch, although the switch can not be closed permanently; that is, the operator may try to close the switch and in doing so draw an injurious arc on the contacts. In carrying out my present invention, therefore, I overcome this objection by providing means whereby after the switch has once opened it cannot be closed until the temperature has dropped to a predetermined point. The means for accomplishing this object may be in the nature of a thermostatic element which, as soon as the switch opens, acts as a barrier to prevent the closing of the switch. The arrangement is preferably such that the switch is latched closed and a thermostat is arranged to trip the latch. Means may also be provided whereby the circuit may be opened at any time by the operator and can be again closed by the operator if the temperature is not excessive.

Other objects and purposes of my invention will appear in the course of the following specification in which I have shown my invention embodied in concrete mechanism for purposes of illustration.

In the accompanying drawing illustrating one embodiment of my invention, Figure 1 is a side elevation of my flatiron with the casing in section so as to show the operating parts; Fig. 2 is a plan view of the iron with the casing removed and the switch closed; Fig. 3 is a similar view with the switch open; and Fig. 4 is a diagrammatic perspective view showing the circuit connec-

Referring to the drawings, the heating element 10 is provided for heating the base 11 of the iron in the usual way. This heating unit is not shown in its structural relation with the iron, since it is not a feature of my invention and any form of unit may be used if desired. The unit is held in place by the plate 12 secured to the base by the screws 13. Mounted upon the plate 12 are the switch parts and other coöperating mechanism. As shown, the switch consists of two spring members 14 and 15 which normally assume the open position shown in Figs. 3 and 4. The switch is closed by turning the rod 16, which in turn operates the member 17 to close the switch. In order to latch this switch closed there is provided a resilient thermostatic member 18 which is adapted to bend toward and from the plate upon which it is mounted upon changes of temperature. On the free end of this thermostatic member 18 is a beveled portion 19 which coöperates with a projecting stud 20 on the member 17 so as to act as a latch for holding the switch closed. As the member 17 is moved toward the position shown in Fig. 2, the stud 20 presses upon the beveled portion 19 and forces the member 18 downward. When it reaches the end of the beveled portion and the switch is closed, the member 18 springs upward and holds the stud 20 in place and thereby latches the switch closed. The sliding rod 21 is adapted to be engaged by the finger of the operator and arranged to force the member 18 downward so as to open the switch.

With the arrangement thus far described, when the temperature rises above a predetermined point, the member 18 will bend downward and release the member 17,

111

thereby allowing the switch to open. When the switch has once opened the operator may turn the rod 16 so as to force the switch closed, but the switch cannot be latched closed until the element 18 is again bent upward by the cooling of the iron. The act of the operator in attempting to close the switch, and perhaps making the attempt several times, may injure the contacts by drawing arcs on them. In order, therefore, to prevent any such closing of the contacts until the temperature has dropped to a point where the contacts should be closed and until the contacts can be latched closed, I provide a resilient thermostatic element 22. This element bends in the opposite direction from the element 18 so that when the temperature rises, the beveled end 23 bends upward into the path of the member 17. When, therefore, the switch opens, the projecting lip 24 on the member 17 rides over the end of the member 22, forcing it downward until the end of the thermostatic element is reached, when it snaps upward and latches the member in the position shown in Fig. 4. This prevents the closing of the switch until the temperature drops a predetermined amount, causing the member 22 to bend downward. The result is that when the switch is once opened the rod 16 is locked against movement until such time as the switch should be closed. At this time the rod will be free to turn and close the switch. The temperatures at which both thermostatic elements operate may be regulated in the usual way by means of adjusting screws.

It will be seen that I have provided a very simple arrangement whereby the current may be cut off either automatically or manually and can be turned on again by the operator only when it is safe to have the current turned on. This makes the apparatus proof against injury due to improper handling.

While I have shown my invention embodied in concrete mechanism for purposes of illustration in accordance with the patent statutes, it should be understood that I do not limit my invention thereto except in so far as it is limited by the scope of the claims annexed hereto, since various modifications thereof will suggest themselves to those skilled in the art without departing from the spirit of my invention.

What I claim as new and desire to secure by Letters Patent of the United States, is:—

1. The combination with an electric heater, of a switch in the circuit thereof, and means controlled by the temperature for opening said switch and thermostatically

controlled means for preventing its subsequent closing.

2. The combination with an electric heater, of a switch in the circuit thereof, means for automatically opening said switch, and means controlled by the temperature for preventing the closing thereof.

3. The combination with an electric heater, of a normally open switch in the circuit thereof, means for holding said switch closed, and means controlled by the temperature for preventing the closure of the switch after it has opened.

4. The combination with an electric heater, of a normally open switch in the circuit thereof, a thermostatic element for holding said switch closed, and a thermostatic element for preventing the closure of the switch after it has opened.

5. The combination with an electric heater, of a switch in the circuit thereof, means for causing said switch to automatically open, and thermostatic means for preventing the closure of the switch after it has opened.

6. The combination with an electric heater, of a switch in the circuit thereof, means for automatically opening said switch, manually operated means for closing said switch, and means controlled by the temperature for preventing the closure of the switch after it has opened.

7. The combination with an electric heater, of a switch in the circuit thereof biased to open position, means for closing said switch, and a resilient thermostatic element arranged to prevent the closure of said switch under certain conditions.

8. The combination with an electric heater, of a switch in the circuit thereof biased to open position, operating means for closing said switch, and a pair of thermostatic elements one of which holds the switch operating mechanism in open position under certain temperature limitations and the other holds it in closed position under other temperature limitations.

9. The combination with an electric heater, of a switch in the circuit thereof biased to open position, means for closing said switch, a resilient thermostatic element for holding said switch closed, and a resilient thermostatic element arranged to prevent the closure of said switch under certain conditions.

In witness whereof, I have hereunto set my hand this 12th day of January, 1911.

WILLIAM S. ANDREWS.
